UNITED STATES PATENT OFFICE.

JOHN A. OBERMAIER, OF CHICAGO, ILLINOIS, ASSIGNOR TO WILMORT MANUFACTURING COMPANY, OF CHICAGO, ILLINOIS, A CORPORATION OF ILLINOIS.

SAFETY-MATCH-BOX HOLDER.

Application filed August 9, 1919. Serial No. 316,299.

To all whom it may concern:

Be it known that I, JOHN A. OBERMAIER, a citizen of the United States, residing at Chicago, in the county of Cook and State 5 of Illinois, have invented a certain new and useful Improvement in Safety-Match-Box Holders, of which the following is a full, clear, concise, and exact description, reference being had to the accompanying drawings, forming a part of this specification.

My invention relates to improvements in match box holders and has special reference to holders for the match boxes which are commonly used for containing what are 15 known as safety matches.

This form of match box comprises an outer member open at its ends and an inner tray member in which the matches are arranged lengthwise and which is adapted 20 to be pushed out endwise through one end of the outer member to expose the matches. Stands have been provided for these boxes, comprising a holder into which the box is adapted to be placed lengthwise in upright 25 position and having an upstanding projection at its lower end adapted to project the tray upwardly out of the outer part of the box, as the box is placed in position. Then the projecting part of the tray is usually 30 torn off leaving the ends of the matches projecting and in position to be readily grasped for removal. The side edges of such boxes are usually provided with a suitable chemical preparation upon which the 35 safety match is to be rubbed in order to cause it to be ignited and the holder as commonly constructed exposes the side edges of the match box for this purpose.

The object of my invention is to provide 40 a holder for such boxes which shall be formed of a single piece of sheet metal, which can be manufactured cheaply and quickly by the usual facilities for such work; which shall have upstanding parts struck up 45 from the sheet to cause the tray to be projected and which shall be formed not only to expose the side edges of the match box, but shall also clasp the box with a spring pressure to prevent the inadvertent removal 50 of the box from the holder.

The holder is secured in upright position upon a suitable base having a part upon which the holder is permanently secured by soldering or otherwise.

55 My invention will be more readily under-

stood by reference to the accompanying drawings in which:

Figure 1, is a side elevation of the complete match box holder, showing the box of matches in place therein;

60

Figure 2 is a plan view of the sheet metal blank from which the box holder is formed;

Figure 3 is a side elevation of the formed up holder; and

65

Figure 4 is a bottom plan view thereof.

A complete match box holder comprises a suitable base 1, having a part 2 upon which I mount the holder proper 3.

70

The essential features of the holder 3 are that it shall retain the match box 4 in upright position, that it shall expose the side edges 5 thereof so that the match heads may be rubbed thereon to ignite them, and that the inner tray 6 containing the matches 7 shall be projected upwardly when the match box is placed in the holder so that the upper ends of the matches shall be projected above the upper end of the match box to facilitate the removal of the matches.

75

All of these essential functions as well as the added one of the holder clasping the match box with spring pressure for retaining the box against inadvertent removal are inherent in the holder of my invention.

80

In Figure 2 I have illustrated the blank 8 out of which I make the holder 3. This blank comprises a flat elongated piece of sheet metal rectangular in form and having its corners rounded off to remove sharp corners and give a more finished appearance.

85

The width of the blank is coincident with the width of the box 4 and it is long enough to provide two sides 10 equal in length to the length of the box and a bottom 11 of a width, lengthwise of the blank, equal to the thickness of the box 4, so that when the blank is bent into the form shown in Figure 3 upon the dotted lines 12 shown on Figure 2 the side members 10 shall be spaced apart far enough to nicely receive the box between them. I preferably form the two sides 10 inclined inwardly towards each other so that it is necessary to spring them outwardly to enter the box 4 between them. This causes the side members 10 to clasp the box with spring pressure and retain it against accidental removal.

95

To cause the tray member 6 to be projected when the box 4 is placed in the holder and to retain the box in the holder against

100

105

110

being pushed out sidewise when the matches are rubbed on the side edges of the box, I strike up projections or tongues 13 out of the body of the blank before the same is 5 bent.

These projections 13 are formed out of the bottom portion 11 of the blank, they are rectangular in shape and are formed by severing them upon three lines 14, 15 and 16, 10 and then bending them along the fourth side 17 so that they stand up from the bottom 11 at right angles thereto and so as to be midway between the sides 10 when they are formed up.

15 The fourth side 17 upon which these projections are bent is parallel with and adjacent to the side edges 18 on the blank so that when these tongues are bent up, as shown in Figure 3, they will be spaced apart 20 transversely of the blank a sufficient distance to cause them to enter within the sides 5 of the outer box member 4 and engage the lower wall 19 of the inner or tray member 6 and cause the same to be projected as the 25 box is inserted into position. These projections 13 are enough narrower than the bottom 11 to provide spaces between their side edges and the sides 10 of the holder to receive the side walls of the box 4, when 30 the same is entered into the holder. Furthermore these projections thus arranged lie flat against the inner surfaces of the sides 5 of the box 4 and assist in preventing the box being tipped over or pushed out 35 sideways in lighting a match.

The projections 13 as indicated in Figure 2 are short enough to leave a central integral bar 20 between their inner ends and by which I mount the holder proper 3 upon the base by soldering or otherwise securing 40 this bar 20 upon the upper part thereof.

The box holder proper of my invention can be manufactured cheaply and rapidly by well known sheet metal stamping and forming processes. It is light in weight, 45 neat in appearance and serves to properly hold a safety match box.

While I have shown and described a specific form of my invention and indicated a preferred method of manufacture, my invention is not thus limited.

I claim:

A match box holder comprising, in combination, a single piece of metal bent to a U-shape with a bight equal to the depth of 55 a match box, and arms of a width substantially equal to the width of a match box, the length of said arms being somewhat greater than the length of a match box, and integral projections struck up out of said bight to a 60 distance greater than the difference between the length of a match box and the length of said side portions, whereby said integral projections abut the match box itself to hold it projecting above said side portions, and 65 permit the cover to slide below said side portions.

In witness whereof I hereunto subscribe my name this 6th day of Aug., 1919.

JOHN A. OBERMAIER.
